UNITED STATES PATENT OFFICE.

HARRY F. BENSON, OF HOLYOKE, MASSACHUSETTS, ASSIGNOR TO WORTHINGTON
PUMP AND MACHINERY CORPORATION, OF NEW YORK, N. Y., A CORPORATION
OF VIRGINIA.

HYDRAULIC CONDENSER AND ASPIRATOR.

Application filed February 3, 1921. Serial No. 442,028.

To all whom it may concern:

Be it known that I, HARRY F. BENSON, a citizen of the United States, residing at Holyoke, county of Hampden, and State of Massachusetts, have invented certain new and useful Improvements in Hydraulic Condensers and Aspirators, fully described and represented in the following specification and the accompanying drawings, forming a part of the same.

This invention relates to a condenser or aspirator of the class adapted to mechanically entrain the fluid acted upon.

In the present invention special advantages are derived by the utilization of the axial flow principle in which one impeller, by reason of its combined axial, radial, and tangential components, delivers to another impeller a conical series of ribbon-like jets of motive fluid which are particularly effective for entraining other fluids such as liquids, gases or vapors, the last mentioned impeller receiving and ejecting the combined motive and entrained fluids and also assisting entrance into the condenser or aspirator of the fluid to be entrained.

The axial flow principle of operation provides a device which, when operating as a condenser, tends to self-regulation in that, as the vacuum increases, more fluid is caused to be delivered by the motive fluid impeller and thus overcomes any tendency of the ejecting impeller to remove less of the entrained fluid, by reason of the increased pumping effect produced by the additional motive fluid thus accumulating in the vanes of the ejecting impeller.

Also, employment of this principle effectively utilizes the maximum radial area presented by the vanes of the impellers to the fluids entering the same, with the result that a smaller size device may be employed for a given capacity than where other types are used, and a higher speed may be taken advantage of.

A further feature of the invention is that no outside pump is required for delivering the motive fluid, as the axial flow impellers perform all the pumping action necessary.

In the drawings:

Figure 1 is a vertical cross section of a condenser or aspirator embodying this invention.

Fig. 2 is a developed plan of the axial flow vanes of the motive fluid impeller.

Fig. 3 is a developed plan of the axial flow vanes of the ejector impeller.

Fig. 4 is a section on the line 4—4 of Fig. 1.

Fig. 5 is a fragmentary view, in vertical cross section, of the invention when embodying fixed diffusion vanes.

Fig. 6 is a developed plan of the fixed diffusion vanes.

Referring to the drawings:

The condenser or aspirator, as herein illustrated for the purpose of disclosing the invention, is of the rotary type and comprises a casing A formed of parts 1 and 2 flanged as at 3 and 4, respectively, for uniting the parts.

The part 1 carries the motive fluid inlet 5 which terminates in the conically flared outlet 6, the lip of which provides a guiding means for the projected motive fluid passing the interior surface and for the fluid to be entrained which passes over the outer surface. This conically flared outlet 6, in combination with the impeller housed therein and to be hereinafter described, also serves to divide the motive fluid inlet 5 from the vacuum chamber 7.

The part 2 of the casing A forms the discharge or pressure chamber and is provided with an outlet 9 for the combined motive and entrained fluids.

At each side of the casing A and concentric with the conically flared outlet 6 are the exterior bearings 13 and 14 which are provided with suitable packing means, not shown, and it is to be especially noted that by reason of their location the vacuum chamber 7 is not exposed to any packed bearings which might permit leakage with consequent diminution of the vacuum.

A shaft 15 is journaled in bearings 13 and 14, one end of which is carried in the end thrust bearing 13^a adjacent the bearing 13, while the other end of said shaft may be connected with a prime mover.

The shaft 15 has fixed thereto an axial flow impeller 16 located in the throat of the flared motive fluid outlet 6 and provided with peripheral vanes 18 which, when developed, appear as in Figure 2. The vanes 18 are directed at an angle to the impeller axis and have thin entrance edges while the sides are curved and slightly diverge toward the outlet finally trailing off at approximately right angles to the impeller 110

axis and providing constricted outlet openings 19, as compared with the entrance areas 20, which thus effect the discharge of a series of ribbon-like jets of motive fluid which are given such a direction and velocity due to the axial, tangential, and radial flow components of this type of impeller that the discharge jets are caused to concentrate in a conical spray.

10 The shape of the inlet 5 and the throat of the motive fluid outlet 6 lead the motive fluid to the impeller in a fluid column which encompasses the impeller 16.

15 Fixed to the shaft 15 and dividing the vacuum chamber 7 from the discharge or pressure chamber is a second and larger axial flow impeller 21 hereinafter referred to as the ejector impeller. The impeller 21 comprises a central web having a sloping curved 20 surface high at the center on the side adjacent the impeller 16 to provide a hub approximately the size of the hub of the impeller 16. The impeller 21 is spaced properly on the shaft 15 so that clearance is provided 25 between the said impeller 21 and the flared motive fluid outlet 6 for the ribbon-like jets discharged by the vanes 18 of the impeller 16, and which jets are maintained in their projected conical series or spray 30 leaving the impeller 16 by the guiding action of the inner surface of the motive fluid outlet 6 and thus are directly received by the vanes 23 of the axial flow impeller 21. These vanes 23, when developed as shown in 35 Figure 3, are angularly directed with respect to the impeller axis and are thin at the receiving edges and have diverging walls thereby providing angularly directed converging discharge passages which receive the 40 combined motive and entrained fluids to be ejected from the device, and also function to further concentrate the entrainment which has been previously accomplished by the supply of fluid to be entrained entering at 45 8 and being directed, by the exterior flared surface of the motive fluid outlet 6, in a superimposed film onto the surface of the conical spray B of ribbon-like jets. The pumping action of the impeller 21, assisting 50 entrance into the vacuum chamber 7 of the fluid to be entrained, tends to draw the directed fluid to be entrained into intimate association with the fluid of the conical spray B.

55 In the modification shown in Figure 5, the addition of fixed diffusion vanes 24 on the discharge side of the ejector impeller transforms the kinetic energy of the combined fluids leaving the impeller into pressure. These vanes, when developed as shown in Figure 6, have knife-like entrance edges with walls that diverge toward the outlet side thus providing constricted or convergent outlet passages directed at an obtuse angle with respect to the vanes of the eject-

ing impeller and the connecting rings 25 and 26 of which also converge toward the outlet side.

For use as an exhauster the vacuum chamber inlet 8 is connected to the area to be exhausted and motive fluid supplied to the inlet 5; thus connected and operated the device is capable of economically maintaining a high vacuum.

If used as a condenser the steam, or other vapors, is passed into the vacuum chamber inlet 8 and the condensing motive fluid is supplied to the inlet 5 from which it is delivered by the axial flow motive fluid impeller 16 in the manner described and condenses and entrains the steam, or other vapors, and the combined fluids are then discharged by the ejecting impeller 21.

It is conceivable that where high fluid pressure is initially available the impeller 16 may be held stationary with respect to the ejecting impeller 21 in which case it will become merely a directing means for delivering the conical spray of motive fluid in the same manner as previously described.

I claim:

1. In a condenser or aspirator, axial flow means delivering an annular jet of motive fluid, means admitting fluid for entrainment by said motive fluid, and a rotary ejector 95 assisting entrance of the fluid to be entrained and receiving and discharging the combined motive and entrained fluids.

2. In a condenser or aspirator, axial flow means delivering an annular spray of motive 100 fluid, means for admitting fluid for entrainment by said spray, and a rotary ejector assisting entrance of fluid to be entrained and receiving the combined motive and entrained fluids.

3. In a condenser or aspirator, axial flow means delivering an annular series of jets of motive fluid, means for admitting fluid for entrainment by said jets, and a rotary ejector assisting entrance of fluid to be entrained and receiving the combined motive and entrained fluids.

4. In a condenser or aspirator, axial flow means delivering a conical spray of motive fluid, means for admitting fluid for entrainment by said spray, and a rotary ejector assisting entrance of fluid to be entrained and receiving the combined motive and entrained fluids.

5. In a condenser or aspirator, axial flow 120 means delivering a conical series of jets of motive fluid, means for admitting fluid for entrainment by said jets, and a rotary ejector assisting entrance of fluid to be entrained and receiving the combined motive 125 and entrained fluids.

6. In a condenser or aspirator, an axial flow rotor delivering an annular spray of motive fluid, means for admitting fluid for entrainment by said spray, and a rotary 130

- ejector assisting entrance of fluid to be entrained and receiving the combined motive and entrained fluids.
7. In a condenser or aspirator, an axial flow rotor delivering an annular series of jets of motive fluid, means for admitting fluid for entrainment by said jets, and a rotary ejector assisting entrance of fluid to be entrained and receiving the combined motive and entrained fluids.
8. In a condenser or aspirator, an axial flow rotor delivering a conical spray of motive fluid, means for admitting fluid for entrainment by said spray, and a rotary ejector assisting entrance of fluid to be entrained and receiving the combined motive and entrained fluids.
9. In a condenser or aspirator, an axial flow rotor delivering a conical series of jets of motive fluid, means for admitting fluid for entrainment by said jets, and a rotary ejector assisting entrance of fluid to be entrained and receiving the combined motive and entrained fluids.
10. In a condenser or aspirator, an axial flow rotor delivering an annular spray of motive fluid, means for admitting fluid for entrainment by said spray, and an axial flow impeller assisting entrance of fluid to be entrained and receiving the combined motive and entrained fluids.
11. In a condenser or aspirator, an axial flow rotor delivering an annular series of jets of motive fluid, means for admitting fluid for entrainment by said jets, and an axial flow impeller assisting entrance of fluid to be entrained and receiving the combined motive and entrained fluids.
12. In a condenser or aspirator, an axial flow rotor delivering a conical spray of motive fluid, means for admitting fluid for entrainment by said spray, and an axial flow impeller assisting entrance of fluid to be entrained and receiving the combined motive and entrained fluids.
13. In a condenser or aspirator, an axial flow rotor delivering a conical series of jets of motive fluid, means for admitting fluid for entrainment by said jets, and an axial flow impeller assisting entrance of fluid to be entrained and receiving the combined motive and entrained fluids.
14. In a condenser or aspirator, a casing, a shaft extending through said casing, a rotor mounted on said shaft at one side of said casing for producing continuously flowing jets of motive fluid, and another rotor on said shaft spaced from the first mentioned rotor for inducing a flow of fluid upon said jets so as to be entrained thereby, said last mentioned rotor discharging the mixture of motive and entrained fluids.
15. In a condenser or aspirator, a casing, a shaft extending through said casing, an axial flow rotary pump mounted on said shaft for producing a conical series of ribbon-like jets of motive fluid, guiding means surrounding the rotary pump, the interior of said guiding means assisting to maintain the conical configuration of the series of jets and the exterior thereof serving to direct a fluid to be entrained upon the motive fluid jets, and a single rotor mounted upon said shaft and spaced from the pump for inducing an inflow of fluid to be entrained and for discharging the mixture of motive and entrained fluids.
16. In a condenser or aspirator, a casing, axial flow means for motive fluid jets, axial flow means for inducing flow of fluid to be entrained, the motive fluid jets discharging into said last mentioned axial flow means, and means directing fluid to be entrained upon said jets in the form of a superimposed layer, said last named axial flow means also serving to discharge the mixture of motive and entrained fluids.
17. In a condenser or aspirator, a casing, axial flow means for motive fluid jets, axial flow means for inducing flow of fluid to be entrained, the motive fluid jets discharging into said last mentioned axial flow means, means directing fluid to be entrained upon said jets in the form of a superimposed layer, said last named axial flow means also serving to discharge the mixture of motive and entrained fluids, and diffusion vanes on the discharge side of the last named axial flow means.
18. In a condenser or aspirator, a casing, axial flow means at one side of said casing for producing a motive fluid sheet the molecules of which move in combined axial, radial and tangential directions, and another axial flow means inducing a flow of fluid to be entrained upon said sheet, said last named axial flow means serving also to discharge the mixture of motive and entrained fluids.
19. In a rotary condenser or aspirator, a casing provided with a motive fluid inlet and a delivery outlet, an axial flow ejector separating the inlet from the outlet, and an axial flow impeller in said inlet delivering motive fluid to said ejector.
20. In a rotary condenser or aspirator, a casing provided with a motive fluid inlet and a delivery outlet, an axial flow ejector separating the inlet from the outlet, and an axial flow impeller in said inlet having vanes delivering ribbon-like jets of motive fluid in a conical spray to said ejector.
21. In a rotary condenser or aspirator, a casing provided with a motive fluid inlet and a delivery outlet, an axial flow ejector separating the inlet from the outlet, and an axial flow impeller in said inlet for delivering motive fluid to said ejector and having vanes forming angularly axially directed

passages each constricted at the delivery end and dividing the motive fluid into ribbon-like jets.

22. In a rotary condenser or aspirator, a casing provided with a motive fluid inlet and a delivery outlet, the said inlet having a flared mouth, an axial flow ejector separating the inlet from the outlet, an axial flow impeller in said inlet and having vanes forming angularly axially directed passages each constricted at the delivery end and projecting the motive fluid toward said ejector in ribbon-like jets maintained in a concentrated conical spray by said flared outlet mouth of the inlet.

23. In a rotary condenser or aspirator, a casing provided with a motive fluid inlet

and a delivery outlet, the said inlet having a mouth provided with interior and exterior flared surfaces, an axial flow ejecting impeller, means admitting fluid to be entrained and entering said casing between the inlet and said ejecting impeller and received on the flared exterior of the motive fluid inlet, and an axial flow impeller in said inlet for delivering a conical series of jets of motive fluid toward said ejecting impeller, the flared inner surface of said inlet maintaining said jets in the conical spray and the exterior surface directing the fluid to be entrained onto said conical spray.

In testimony whereof, I have hereunto set my hand.

HARRY F. BENSON.
